(57) **CLAIM**

The ornamental design for an outside bumper for a rail fastener orienter, as shown and described.

DESCRIPTION

FIG. 1 is a top perspective view of the present outside bumper for a rail fastener orienter;

FIG. 2 is a front view of same;

FIG. 3 is a rear view of the bumper of FIG. 1;

FIG. 4 is a bottom view of same;

FIG. 5 is a top view of the bumper of FIG. 1;

FIG. 6 is a left side view of same; and,

FIG. 7 is a right side view of same.

The structure shown in broken lines is for environment purposes only and does not form part of the claimed invention.
